(57) **CLAIM**

We claim the ornamental design for a lamp, as shown and described.

DESCRIPTION

FIG. 1 is a perspective view of a lamp;

FIG. 2 is a front side elevation view thereof.

FIG. 3 is rear side elevation view thereof.

FIG. 4 is a left side elevation view thereof.

FIG. 5 is right side elevation view thereof.

FIG. 6 is a top view thereof; and,

FIG. 7 is a bottom view thereof.

Broken lines in the drawings illustrate portions of the lamp that form no part of the claimed design.
